UNITED STATES PATENT OFFICE.

MARY A. THOMSON, OF NEW YORK, N. Y.

DESIGN FOR A STOCKING DOLL.

Application filed October 9, 1922. Serial No. 3,921. Term of patent 7 years.

To all whom it may concern:

Be it known that I, MARY A. THOMSON, a citizen of the United States, residing at New York, county and State of New York, have invented a new, original, and ornamental Design for Ornamental Stocking Doll, of which the following is a specification, reference being had to the accompanying drawing, forming part thereof.

The figure is a front elevation of a doll showing my new design.

I claim:

The ornamental design for a stocking doll, as shown.

In testimony whereof I have hereunto set my hand on this 6th day of October A. D., 1922.

MARY A. THOMSON.
